UNITED STATES PATENT OFFICE.

WILLARD E. LAPE, OF SYRACUSE, NEW YORK.

DESIGN FOR A FRAME FOR LAWN-MOWERS.

SPECIFICATION forming part of Design No. 22,431, dated May 5, 1893.

Application filed March 21, 1893. Serial No. 467,076. Term of patent 14 years.

To all whom it may concern:

Be it known that I, WILLARD E. LAPE, a citizen of the United States, residing at Syracuse, county of Onondaga, and State of New York, have invented and produced a new and original Design for Frames for Lawn-Mowers, of which the following is a description, reference being had to the accompanying drawing, in which I show an isometrical view of my design frame complete, the remaining portions of the lawn-mower mechanism being removed.

The leading feature of my design consists of a frame —A— substantially rectangular, having two of its corners —a— slightly

rounded and its remaining corners —b— somewhat angular and having raised portions or beadings —c— upon the upper and lower outer lateral faces of the frame.

What I claim is—

The frame for a lawn-mower, substantially as herein described and shown.

In witness whereof I have hereunto set my hand this 18th day of March, 1893.

WILLARD E. LAPE.

In presence of—

HOWARD P. DENISON,
C. B. KINNE.
